UNITED STATES PATENT OFFICE.

WILLIAM P. MILLER, OF TIPTON, MISSOURI.

IMPROVEMENT IN NUT-LOCKS.

Specification forming part of Letters Patent No. 222,929, dated December 23, 1879; application filed August 2, 1879.

To all whom it may concern:

Be it known that I, WILLIAM P. MILLER, of Tipton, in the county of Moniteau and State of Missouri, have invented a new and Improved Nut-Lock, of which the following is a specification.

Figure 1 is a perspective view of the device as applied to a rail. Fig. 2 is a cross-section of the same on line *x x*, Fig. 1. Fig. 3 is a detail hereinafter referred to.

Similar letters of reference indicate corresponding parts.

The object of this invention is to furnish a cheap, simple, effective, and easily-adjusted nut-lock.

In the drawings, A represents a railroad-rail; B, the fish-plates; C, the bolts; D, the nuts; E, the washer-plate set under the nuts and having its ends *a' b'* coiled, made elastic, and hooked upward. F is the lock-plate, and G, Fig. 3, is a wrench. *c'* is a hole in the end *a'* of the washer-plate, for a prong on the other end of the wrench to fit into when it is desired to unhook the washer-plate.

The fish-plates being in place on the rails, and the bolts passed through them, the washer-plate is set over the bolts and the nuts put on the bolts and turned down tightly. The ends of the washer-plate are then turned back

or straightened sufficiently to permit the lock-plate to be placed over the nuts, and then are permitted to spring over the ends of the lock-plate to hold it in position. It will be seen that each slot in the lock-plate embraces two nuts instead of one, as is commonly the case, and it is found that this arrangement makes the plate more easy of adjustment and of less weight and cost.

The arched notch *d'*, cut in the lower edge of the plate, is to accommodate the head of the spike that assists in holding the rails to the sleeper.

It is obvious that in the ease with which this lock can be applied or removed, in durability, and simplicity, this lock possesses many advantages over those commonly in use.

I am aware that slotted lock-plates have been secured by turning the ends of subjacent washer-plates over them; but

What I claim as new is—

As an improved means for securing lock-plates in nut-locking devices, the steel washer-plate E, having the upturned spring ends *a' b'*, substantially as shown and described.

WILLIAM P. MILLER.
